UNITED STATES PATENT OFFICE.

CURT WOLFELT, OF NEW YORK, N. Y.

ORNAMENTAL SHOE AND METHOD OF ORNAMENTING SAME.

Application filed June 14, 1926. Serial No. 115,718.

My present invention relates generally to the ornamentation of sheet material, and has particular reference to ornamental footwear, involving co-ordinately a method of treating sheet material to produce such ornamentation, and more particularly to a method of ornamenting shoes.

It is an object of the present invention to produce ornamental sheet material, particularly of the flexible non-woven type, such as leather. The invention has for its object the treatment of such material in accordance with an extremely simple and inexpensive method to produce the desired effect.

More particularly, the invention contemplates the production of ornamental articles of footwear, particularly of the type worn by women, the ornamentation being of a character which is not only inexpensive from the standpoint of its production, but which produces effects which are both unique and highly attractive.

In the production of ornamentation of the type herein referred to, and particularly in the production of ornamentation for shoes, one of the important factors to be considered is that of color, the proper combinations of color being highly desirable because of the wide variety of ornamentation which is made possible by the use of this factor alone. It is an object of the present invention to provide an ornamentation wherein the element of color and color combinations may be made to play an important part with comparative simplicity. More particularly, it is an object of the invention to provide ornamentation of a character which may permit the proper co-relation of at least three colors or other contrasting appearances with a minimum of manufacturing expense.

It is another object of the invention to provide an ornamentation which presents a peculiarly attractive appearance entirely regardless of color considerations, and which is peculiarly adaptable to a wide variety of modifications.

Co-ordinately, my invention relates to a method of treating sheet material, such as leather, and particularly to a method of treating a shoe, or portions thereof, in order to produce ornamentations of the character referred to. My invention also contemplates the production of ornaments by means of this method which may be independently produced and subsequently affixed or associated with the shoe.

A feature of my invention lies in treating a sheet of flexible material, such as the outer layer of the upper of the shoe, so as to produce portions which are individually adjustable with respect to each other and to the balance of the sheet of which they form parts, and thereupon individually manipulating these portions so as to deflect them in a predetermined manner out of the normal surface contour of the sheet. More particularly, these portions are artistically configured and arranged with respect to each other in accordance with predetermined design, and they are thereafter manipulated in accordance with the design contemplated to produce a composite effect of the character desired.

Another feature of the invention lies in providing the material in which these portions are produced with opposite surfaces of contrasting appearance, and manipulating the portions in a manner which will display both surfaces in accordance with predetermined design so as to produce an enhanced effect.

A still further feature of the invention lies in providing the portions with an underlay which may embody a still further contrasting appearance, and manipulating the portions so as to render portions of the underlay visible and thereby permit a still further contrasting effect to increase the attractiveness of the ultimate ornamentation.

In a preferred method of carrying out the invention, the portions which are individually adjustable are arranged and constructed to provide a series of adjacent parallel elongated strips which are twisted upon themselves. Moreover, these strips are preferably twisted through substantially 180°, thereby causing the under-surfaces of the strips to form a composite outer display surface lying substantially along the initial surface contour of the material.

In general, it is an object of the invention to provide an ornamental portion for sheet material, and particularly for a shoe, in accordance with a method which is not only inexpensive from the standpoint of labor, but also from the standpoint of material; which produces a very attractive and unique appearance which reflects careful workmanship and artistic ability; and which is capable of an almost unlimited variety of modifications, both as to contour, position, composite effect, and color combinations.

For the attainment of the foregoing objects and such other objects as may herein-after appear or be pointed out, I have illustrated one embodiment of my invention in the accompanying drawings in which the invention is shown as being embodied in an illustrative manner upon a lady's shoe of the character herein referred to. In the drawings,

10 Fig. 1 is a plan view of an illustrative ornamental portion of the shoe with parts broken away for the sake of clearness;

Fig. 2 is an enlarged view of a fragment of Fig. 1, showing details of construction;

15 Fig. 3 is a cross-sectional view taken along the line 3—3 of Fig. 1;

Fig. 4 is a cross-sectional view along the line 4—4 of Fig. 1; and

20 Fig. 5 is a perspective view of a completed shoe ornamented in accordance with the present invention.

Referring to the drawings, it will be observed that I have shown a shoe in Fig. 5 wherein the tip has been provided with an 25 ornamentation produced in accordance with the present invention, and wherein the rear portion of the shoe has been similarly ornamented. In Fig. 1, I have shown the tip ornamentation upon a relatively enlarged 30 scale, and it will be observed that in the illustrated form I have utilized the outer layer of the shoe upper as the sheet of flexible material which constitutes the basis of the ornamentation. This sheet is denoted by 35 the reference numeral 10, and I have illustrated this sheet as being superposed upon an underlay 11 which may be retained in place either by lines of stitching 12, by adhesive means, or by direct marginal attachment to the sole 13 of the shoe.

40 The ornamentation illustrated is produced by making a series of substantially parallel cuts through the material 10, these cuts thereby defining and providing a series of 45 adjacent portions 14 between the cuts and capable of being individually manipulated with respect to each other and to the balance of the material 10. By virtue of the parallelism of the cuts, the separated portions 50 14 may be made to assume the form of elongated strips, and I have shown these strips individually twisted upon themselves within the areas initially defined by them. I have shown these strips as having their mid-portions 55 twisted through 180°, these mid-portions 15 being retained in such reversed positions by a strap 16, although the employment of a strap for this purpose is more or less optional. The mid-portions 15 constitute a 60 composite ornamental surface which lies substantially in the plane or surface contour of the initial unmanipulated sheet 10.

It will be observed that by twisting the individual strips, openings 17 are provided through the sheet 10. These openings are

substantially rhombic and may, if desired, be utilized for ventilating purposes where the invention is embodied in a shoe, or they may, for example, constitute passages for light rays where the invention is employed upon some such article as a lamp-shade. I have found it more satisfactory to make use of the provision of these openings for the purpose of rendering visible portions of the underlay 11, and with this object in view 75 the surface of the underlay 11 is made either of a different color from the upper surface of the sheet 10, or it is in any other manner made to embody a contrasting appearance.

The provision of the portions 14, whether they be elongated or shaped and positioned in other ways, and the subsequent manipulation of these portions in accordance with the present method, produces by itself an ornamental effect which is both unique and highly attractive. The provision of an underlay 11 is a feature of my invention, but it will be understood that as to certain other phases of the invention, the provision of such an underlay is not essential.

Furthermore, whereas the provision of a contrasting underlay in combination with the manipulated sheet 10 enhances the appearance of the ornamentation, I have found it possible to increase the effectiveness of my ornamentation to a still further degree by providing the sheet 10 itself with opposite surfaces of contrasting nature. Although the leather itself may provide the contrasting surfaces which I have found desirable, nevertheless I find it preferable to line the material 10 with a separate layer of material of decidedly different appearance of color. Thus, in Figs. 2, 3, and 4, I have shown the material 10 provided with a lining 18 which is adhesively associated therewith, although this means of association is a matter of choice. Where a lining 18 is employed, it is preferably of a character which presents a third contrasting appearance in comparison to the appearances of the sheet 10 and the underlay 11. For example, the material 10 may be gray in color, the lining 18 may be pink, and the underlay may be deep red. I have found it particularly suitable to employ as the underlay a material which has a lustrous surface such as that presented by celluloid, thereby rendering still further effects possible by permitting whatever light may enter the openings 17 to be reflected from the colored underlay, or, in certain cases, permitting light rays to pass through the underlay. It will be obvious that in its broadest aspect, my invention is applicable to sheet material in general, and I have illustrated and described my invention as embodied in a shoe for the reason that it embodies features which render such an application particularly favorable. In the first place, the incidental production of openings,

such as the openings 17, renders ventilating effects possible, although these effects are incidental to the primary purposes of the ornamentation. In the second place, an ornamentation is produced without the addition or application to the shoe of extra layers or elements. In this way, the final weight of the shoe is retained at a minimum, and the extra expense of separately attaching ornamental portions is obviated. It will be observed, however, that in certain cases it may be desirable to embody my invention in separately applicable ornamented portions. In the third place, the provision of a color effect involving at least three colors is made possible by an extremely simple means, entailing no separate addition or inlaying of varicolored elements or portions. In the fourth place, the present invention permits me to utilize the inherent contrasting appearances of the opposite surfaces of the shoe upper for purposes of ornamentation. The leather which is used for shoes of this character is of an extremely high quality, and its underside, heretofore entirely invisible, has been utilized as a factor of ornamentation. In the fifth place, the upper of a shoe presents a substantially rigid contour whereon the ornamentation may be rendered extremely effective because of this fact. Moreover, where the twisted strips are retained in twisted positions by means other than adhesion, a shoe presents numerous elements, such as the strap 16 or the rim 20, whose presence may be utilized for this purpose.

It will now be obvious that still further contrasts of appearance may be taken advantage of by virtue of the possible contrasting appearances of the retaining elements, such as the strap 16 or the rim 20. Moreover, it will be obvious that the edges of the strips themselves may be taken advantage of in a proper manner, from the standpoint of outward appearance, in the design of the finished ornamentation.

It will thus be seen that I have provided a means for ornamenting material such as leather, which will find wide applicability in the arts. For example, the ornamentation of the present invention may be advantageously used in the manufacture of lamps, hats, hand-bags, or similar articles, wherein sheet material of the leather or felt type is a salient element of construction. It may conceivably be employed in connection with woven fabrics, although its employment for this purpose might be beset with difficulties due to the raveling of the material. Furthermore, it will be obvious that a wide variety of modifications may be employed. For example, the contour of the strips may be altered, the relative disposition of the strips may be changed, and the strips themselves may be twisted either as shown in the

accompanying drawings or in alternately opposite directions, or through 360°, or otherwise. In the embodiment illustrated, the opposite ends of the strips are rigidly attached to each other; it may be desirable in certain cases to extend the slits or cuts to the edge of the sheet material, thereby severing the strips at one end thereof. The provision of retaining means such as the strap 16 is also more or less optional, the normal tension and contour of the tip of the shoe, where a shoe is the article ornamented, being a possible means of retaining the strips in adjusted positions without use of any further instrumentalities.

Thus, it will be seen that many changes in the details herein described and illustrated for the purpose of explaining the nature of my invention may be made by those skilled in the art without departing from the spirit and scope of the invention as expressed in the appended claims. It is therefore intended that these details be interpreted as illustrative and not in a limiting sense.

Having thus described my invention and illustrated its use, what I claim as new and desire to secure by Letters Patent is:

1. In a shoe, an ornamental portion comprising a plurality of longitudinally twisted strips.
2. In a shoe, an ornamental portion comprising a plurality of longitudinally twisted strips, said strips being formed of an integral blank of sheet material by making a series of substantially parallel cuts therein.
3. In a shoe, an ornamental portion comprising a sheet of material having cuts therethrough positioned to provide portions between the cuts which are capable of being individually twisted, said portions being retained in twisted positions to render their under-sides visible.
4. In a shoe, an ornamental portion comprising an integral sheet of flexible material having a series of cuts therethrough positioned to provide a series of adjacent portions between the cuts which are capable of being individually twisted out of the plane of the material, said portions being twisted to render their under-sides visible, and being so shaped and positioned relatively of each other that the twisting thereof will provide an ornamental composite portion constituted of said under-sides.
5. In a shoe, an ornamental portion comprising a series of adjacent individually twisted portions of sheet material, and an underlay of contrasting material visible through the spaces provided by twisting said portions.
6. In a shoe, an ornamental portion comprising an integral sheet of material provided with a series of substantially parallel slits to provide individually twistable strips

between said slits, said strips being twisted, and a contrasting underlay visible through the spaces produced by said twisting.

7. In a shoe, an ornamental portion comprising a sheet of material having contrasting opposite surfaces, said sheet being provided with individually and independently adjustable portions formed integrally therewith, and said portions being individually twisted to render portions of the contrasting under-surface visible.

8. In a shoe, an ornamental portion comprising a lined piece of flexible material positioned on the shoe in a manner which renders the lining normally invisible, said sheet being provided with cuts therethrough positioned to provide individually twistable portions between said cuts, and said twistable portions being twisted to render the lining on their under-sides visible.

9. In a shoe, an ornamental portion comprising a flexible sheet of material having contrasting opposite surfaces, an underlay for said sheet having a third contrasting surface, said sheet being provided with independently adjustable integral portions, and said portions being individually adjusted to reveal both their under-sides and portions of the underlay.

30 10. The herein described method of ornamenting shoes which includes the steps of forming a series of substantially parallel slits in the upper of the shoe, and twisting the portions between said slits.

35 11. The herein described method of ornamenting shoes which comprises lining a portion of the upper of the shoe with an underlay of contrasting material, forming a series of cuts in the upper, and individually twisting the portions of the upper which lie between said cuts, thereby rendering portions of the underlay visible.

40 12. The herein described method of ornamenting shoes which includes the steps of lining a portion of the upper with a sheet of

contrasting material, providing an underlay 45 of contrasting material under said lined portion, forming a series of cuts through said lined portion, and individually twisting those portions which lie between said cuts, thereby rendering portions of both the lin- 50 ing and the underlay visible.

13. The method of ornamenting sheet material which comprises the steps of forming substantially parallel slits therein, and twisting the strips thereby produced.

55 14. Ornamental sheet material comprising a series of adjacent separated strips integral with the sheet and formed by cutting the sheet along parallel lines, said strips being individually twisted within their own areas 60 to display their under-sides.

15. Ornamental sheet material provided with a series of parallel slits therethrough, said slits defining a series of separated strips 65 of the sheet between them, and said strips being individually twisted upon themselves in one direction and within their own initial areas, whereby the under-sides of the strips are displayed, and whereby openings are produced through the material adapted to 70 permit the passage of light rays therethrough.

16. An ornamentation comprising superposed layers of sheet material, the upper one thereof having spaced cuts therein to provide portions between the cuts which are individually adjustable out of normal position, said portions being individually twisted to a degree which renders portions of their edges and under-sides visible, and said 80 under-portion embodying an appearance which contrasts with both the upper and under-sides of said portions whereby a composite ornamentation is produced permitting desired combinations of at least three contrasting appearances.

In witness whereof, I have signed this specification this 10th day of June, 1926.

CURT WOLFELT.
